(57) **CLAIM**

I claim an ornamental design for a trigger sprayer, as shown and described.

DESCRIPTION

FIG. 1 is a front-perspective view of a trigger sprayer showing my new design;

FIG. 2 is a side view of the trigger sprayer shown in FIG. 1; FIG. 3 is a side view of the trigger sprayer shown in FIG. 1; FIG. 4 is a front view of the trigger sprayer shown in FIG. 1; FIG. 5 is a rear view of the trigger sprayer shown in FIG. 1; FIG. 6 is a top view of the trigger sprayer shown in FIG. 1; FIG. 7 is a bottom view of a trigger sprayer shown in FIG. 1; FIG. 8 is a rear-perspective view of the trigger sprayer shown in FIG. 1; and,

FIG. 9 is a perspective view of a bottle combined with the trigger sprayer shown in FIG. 1.

The broken lines in the drawings depict unclaimed elements of the trigger sprayer and environmental subject matter only and form no part of the claimed design.
